REGULATING PUMP

Samuel Meiswinkel, Gaggenau, Germany, assignor to Daimler-Benz Aktiengesellschaft, Stuttgart-Unterturkheim, Germany

Application January 17, 1939, Serial No. 251,326
In Germany January 22, 1938

35 Claims. (Cl. 123—140)

This invention relates to an apparatus for limiting the maximum speed of injection internal combustion engines by regulating the fuel feed, and has for its object to effect in a very simple manner and without separate mechanical or pneumatic auxiliary equipments, a reliable and accurately operating control of the internal combustion engine for the purpose of limiting its maximum speed of rotation.

For limiting the maximum speed of injection internal combustion engines by the regulation of the fuel feed, a constant factor and a variable factor are, according to the invention, brought into alternating relationship in such a manner that when the constant factor is exceeded, the fuel feed to the cylinders is reduced by the variable factor, the variable factor being a function of the speed of rotation of the engine. The said variable factor is determined by the quantity of fuel flowing back from the pump cylinder per unit of time and increasing as the speed of rotation increases. The quantity of fuel flowing back per unit of time acts directly or indirectly on the adjustment of a slide valve controlling the feed passages, the returning fuel and the fuel fed from the tank being brought together each from one side of the slide valve, so that when a certain speed is attained a dynamic pressure is produced which constitutes the means for controlling the fuel feed.

For carrying out the objects of this invention, a fuel pump with controlled commencement of feed and constant end of feed is used so that the injection adjustment is automatically coupled with the quantity of fuel fed, that is, retarded ignition takes place at low load and a small quantity fed, and advanced ignition at heavy load which approximately corresponds to the maximum speed. The arrangement is such that the controlling element on the one hand is under the influence of the constant factor and on the other hand under the influence of the variable factor which on exceeding the constant factor adjusts the controlling element and throttles the fuel feed by changing the passage cross-sectional area. For this purpose a controlling element adjustable in opposition to spring action and the pressure in the inlet conduit is arranged in the inlet conduit, said element being adjustable by the changing pressure in the by-pass conduit and thus by throttling, changes the quantity of fuel sucked in by the pump.

The controlling element may consist of one or several rotary slide valves to which the fuel from the tank flows freely from one side but from

the other side (by-pass-fuel) through a nozzle which is arranged in such a manner that, when a predetermined feed is exceeded dynamic pressure is produced on the inlet side of the nozzle and adjusts the controlling element. The throttling device may be constructed as a nozzle with adjustable throttling cross-section. The controlling element itself is, according to the invention, arranged as a rotatable or axially shiftable piston-shaped slide valve in the induction conduit, and has on its periphery one or more controlling apertures or controlling edges which at the adjustment of the slide valve alter by throttling the passage cross-section of the conduit, i. e. the quantity of fuel sucked by the pump. The controlling apertures or edges of the slide valve are at the same time preferably constructed as peripheral tapered grooves or ports varying in depth, which control the inlet bores or channels leading to the pump.

The invention also relates to a device for adjusting the individual pump pistons for the purpose of compensating inaccurate machining.

This independent adjustment is rendered possible, according to the invention, in that the feed pistons, each provided in an upper portion with a bevelled edge, and which are not rotatable when running, are turned when adjusting the pump, for example on the test bench, and fixed in the position which has been found to be correct, so that the necessary quantity delivered by these pistons can be very accurately controlled in each case. The adjustment is effected, for example, by means of a toothed sector rigidly connected with the piston and which allows of an adjustment through a very small angle. Thus, the bevelled edge of each piston is adjusted relatively to the admission channels in such a manner that the commencement of feed of the individual pistons can be accurately determined independently of each other. The pistons are secured in the determined position, for example from the exterior, by means of a set screw which locks the toothed sector and consequently the piston rigidly connected therewith.

This adjusting device possesses the advantages that unavoidable inaccuracies in machining can be compensated in a simple manner when the pump is being adjusted, and that the adjustment can be carried out in a short time from the outer side without any fitting work being necessary.

The invention also relates to such a construction of the pump cylinders which enables them to be produced and machined in a particularly simple and cheap manner.

According to the invention, the casing having the bores and passages is made of cast-iron, preferably cast pig iron, and the cylinder bores and also the passages controlled by the piston are bored in separate rigidly inserted liners made of high grade material. The liners made for example of steel are cast, pressed or shrunk into the casing as a solid body before the different holes and passages are bored. The advantages are thus obtained that the machining is extremely simple and the position of the bores and control edges is always accurate.

Several embodiments of the invention are illustrated diagrammatically by way of example in the accompanying drawings in which:

Fig. 1 is a section through the fuel feed pump taken on line 2—2 of Fig. 2 and viewed in the direction of the arrow;

Fig. 2 is a section on line 1—1 of Fig. 1;

Fig. 3 is a top plan view in section on line 3—3 of Fig. 2;

Fig. 4 is a sectional detail view showing an adjustable throttling nozzle;

Fig. 5 is a section through a pump cylinder with adjusting device for the feed piston;

Fig. 6 is a top plan view in section on line 4—4 of Fig. 5; and

Fig. 7 is a section through a pump cylinder with a liner.

The fuel pump 10 has an inlet passage 11 and a return passage 12 which are connected the one with the other by a channel 13. Pump pistons 15 are arranged in the cylinder bores or spaces 14 and moved by suitable cams of a cam shaft 16 driven by the internal combustion engine. Channels or canals 17 lead from the inlet passage 11 to the individual cylinder bores 14 and overflow channels or canals 18 lead from the said cylinder bores 14 to the return passage 12. A slide valve 19 in the form of a piston-shaped hollow sleeve provided at one end with a nozzle or throttle opening 20 moves in the inlet passage 11. The stroke of the slide valve 19 is limited on the right by an adjustable stop screw 21 and on the left by an adjustable stop screw 22. The arbitrary control of the internal combustion engine is effected through the intermediary of the accelerating lever (not shown) which turns the piston 15 or the edge 23 thereof through the regulating or adjusting device 24.

The fuel flows from a container, not illustrated, through a conduit 25 and the openings 46, that is from the side remote from the nozzle 20, to the slide valve 19. The piston 15 controls by suitably shaped edges the admission channel 17 and the overflow channel 18 in such a manner that the fuel is forced through the conduits 26 into the cylinders of the internal combustion engine, and after having performed part of a predetermined stroke, a uniform quantity of fuel is fed through the piston bore 27 and the recess 28 into the overflow channel 18 and thence into the return passage 12. The slide valve 19 has tapered grooves 29 and openings or bores 30 in its walls, which together are arranged to form ports registering with the channel 17 and act in such a manner that the effective cross-section of the inlet passage 11 leading to the cylinders 14 can be altered.

The operation of the regulator is the following:

When the internal combustion engine and consequently the pump shaft 16 are running at a low speed, a quantity of fuel corresponding to the stroke space is sucked into the cylinders 14 as the piston 15 descends and is injected into the cylinders of the internal combustion engine

through a suitable delivery passage at the correct time during the ascent of the said piston. As soon as the recess 28 reaches the overflow channel 18, the excess fuel flows back through the channels 12 and 13 into the inlet passage 11 from which it is again sucked into the cylinders. At the same time the spring 31 presses the slide valve 19 towards the left, so that the conical grooves 29 expose the largest passage cross-section to the cylinders 14. If the speed of the internal combustion engine increases and attains a predetermined maximum, the quantity of fuel flowing back in a unit of time is so high that at the throttle point 20 counter pressure is produced which shifts the slide valve 19 towards the right in overcoming the force of the spring 31 and the pressure of the fuel within the passage 11, and reduces the effective cross-section of the passage 11 to the pistons 15 corresponding to the reduction in cross-section of the tapered grooves 29. Thus, the charge in the cylinder spaces 14 during the descent of the piston will be reduced and a correspondingly less quantity of fuel will be injected into the cylinders of the internal combustion engine. The by-pass quantity per piston stroke remains the same at all speeds. Owing to the drop in pressure which then occurs in the by-pass conduit a slight oscillation of the regulating slide valve 19 will take place until this valve has formed relatively the smallest possible feed cross-section of the entrance to the admission channels 17 necessary for the maximum no-load speed.

Fig. 4 shows a form of construction in which the throttle 20 can be varied in cross-section by a needle 32.

According to the form of construction illustrated in Figures 5 and 6, the pump pistons 15 are pressed tightly against the cams 36 of the fuel pump shaft 16 by springs 33 which bear at one end against a spring washer 34 and at the other end against a spring washer 35. The pistons 15 have milled faces 37 on to which the slotted toothed sectors 38 can be slipped from the side. These toothed sectors 38, which are non-rotatable on the pistons but longitudinally shiftable thereon, are fixed by suitable locking devices shown as set screws 39 from the outer side. By turning the toothed sectors 38 the bevelled edges 23 of the pistons 15 are adjusted relatively to the admission channels 17, and consequently the quantity delivered by the individual pistons can be regulated independently the one of the other. The pistons 15 also have recesses or grooves 29 and bores 27, through which the excess fuel can flow off through the overflow channels 18 to the return passage 12. The channels 17 and 18 are closed at their outer ends by plugs 40 and 41, respectively.

According to the example illustrated in Fig. 7, the cylinders 42 in which the pistons 15 move, are constructed as steel liners 43 which are cast, pressed or shrunk into the casing 10, for example a pig iron casing. The casing may be made of light metal and produced for example by die-casting. The liners 43 are preferably inserted in the casing as solid bodies before the different holes and passages are bored (admission channel 17, overflow-channel 18 and so forth). Thus, the machining of the liner 43 is simplified considerably, the edges of the channels 17 and 18 will be accurate and the resistant material sharp, so that the timing remains constant even after long service. It is evident that the liner 43 may be made not only of steel but also of brass

or of other suitable material. The pistons 15 have rollers 43 which are pressed against the cams 36 by springs 44. The springs bear at one end against spring washers 45 and at the other end against the casing 10.

While the pumps described above and illustrated in the drawings are particularly adapted for use in providing a limited maximum fuel feed to internal combustion engines, it will be obvious that in the broad sense such pumps are of general application wherever a limited maximum output of pumped liquid is desired.

It will therefore be seen that I have provided a construction which satisfies the objects enumerated above and one which constitutes a valuable advance in the art. While I have shown the invention in certain physical embodiments, it is to be understood that modifications of the structure shown may be made by those skilled in this art without departing from my invention as expressed in the claims which follow.

What I claim is:

1. A fuel pump comprising a pump casing provided with separate pump cylinder spaces, a common inlet passage provided with channels leading to the individual spaces, a return passage provided with channels leading from said spaces, a fuel controlling element in the said inlet passage responsive to the pressure of the fuel in said return passage, and a throttling device arranged between the return passage and the inlet passage.

2. A fuel pump comprising a pump casing provided with separate pump cylinder spaces, a common inlet passage provided with channels leading to the individual spaces, a return passage provided with channels leading from said spaces, a fuel controlling element in the said inlet passage responsive to the pressure of the fuel in said return passage, a throttling device arranged between the return passage and the inlet passage, and abutment stops for limiting the movement of the said sliding controlling element in both directions.

3. A fuel pump comprising a pump casing provided with separate pump cylinder spaces, a common inlet passage provided with channels leading to the individual spaces, a return passage provided with channels leading from said spaces, a piston-shaped hollow sleeve in said inlet passage having a throttle opening in the wall of said piston to form a connection between the inlet and return passages, said piston being subjected to the pressure of the fuel within said return passage and said sleeve as a whole being axially shiftable in the inlet passage under the action of such pressure, the walls of said sleeve being provided with throttle openings connecting the interior of said sleeve with the channels leading to the cylinder spaces, and spring means for biasing said sleeve in one direction.

4. Fuel feed controlling apparatus for internal combustion engines comprising, in combination, a device including a pump cylinder space, an inlet passage leading to said cylinder space, a delivery passage leading from said cylinder space, a return passage leading from said cylinder space to said inlet passage, and throttling means intermediate said return and inlet passages for maintaining the pressure of the fuel in said return passage substantially proportionate to the amount of fuel flowing back to said return passage, and means responsive to said pressure for varying the delivery of fuel to the engine.

5. Fuel feed controlling apparatus for internal

combustion engines comprising, in combination, a device including a pump cylinder space, a source of fuel supply for said cylinder space, a delivery passage leading from said cylinder space to said source of fuel supply, and throttling means intermediate said return passage and said source of fuel supply for maintaining the pressure of the fuel in such return passage substantially proportionate to the amount of fuel flowing back through said return passage, and means responsive to said pressure for varying the delivery of fuel to the engine.

6. Fuel feed controlling apparatus for internal combustion engines comprising, in combination, a device including a pump cylinder space, an inlet passage leading thereto, a delivery passage leading therefrom, a return passage leading from said cylinder space to said inlet passage, means for establishing a pressure differential between said inlet and return passages, means responsive to said pressure differential for controlling the delivery of fuel to the engine, and spring means for biasing said controlling means.

7. A fuel pump, comprising, in combination, a pump casing including a cylinder space, an inlet passage, a canal leading to the cylinder space, a delivery passage leading from the cylinder space, a return passage connected to the cylinder space, and a regulating device for controllably interconnecting said inlet passage with said canal, said regulating device being subjected to and movable by the pressure of the fuel in said return passage, and being provided with a throttle opening interconnecting said return passage with said inlet passage.

8. The combination according to claim 7, in which said regulating device includes a hollow sleeve having transverse bores interconnecting said inlet passage with said canal.

9. The combination according to claim 7, in which said regulating device is in the form of an axially adjustable slide valve.

10. The combination according to claim 7, in which said regulating device includes a hollow sleeve closed at one end to form a piston face subjected to the pressure of the fuel in the return passage, said sleeve having transverse bores interconnecting said inlet passage with said canal, said throttle opening extending through said piston face.

11. A pump comprising, in combination, a pump casing having separate pump cylinder spaces, a common inlet passage, canals leading from said passage to individual cylinder spaces, a common return passage, other canals leading from said cylinder spaces to said return passage, and a controlling device in said inlet passage having throttling openings adapted to adjustably control the communication between said inlet passage and the canals leading to the cylinder spaces, said device including means responsive to the pressure in said return passage for varying the effective cross-section of said communicating openings.

12. A liquid pump comprising in combination, a cylinder casing having at least two pump spaces and pistons in said spaces, each piston having a beveled control edge, means for adjusting each piston independently of the other, a common inlet passage leading to said cylinder spaces, a return passage leading from said cylinder spaces to said inlet passage, throttling means intermediate said return and inlet passages for maintaining the pressure of the fuel in said return passage sub-

stantially proportionate to the amount of fuel flowing back through said return passage, and means responsive to said pressure for varying the effective cross-section of said common inlet passage to simultaneously vary the amount of fluid supplied to all the cylinder spaces. 5

13. The combination according to claim 12, in which said independent adjusting means includes a toothed sector longitudinally shiftable upon but non-rotatably connected to each piston. 10

14. The combination according to claim 12, in which said independent adjusting means includes a toothed sector, longitudinally shiftable upon but non-rotatably connected to each piston, and a locking device engaging the toothed 15 sector.

15. The combination according to claim 12, in which said independent adjusting means includes a toothed sector, longitudinally shiftable upon but non-rotatably connected to each piston, and a set screw adjustable from without said pump casing, engaging with the teeth of the toothed sectors. 20

16. The combination according to claim 12, in which said pump casing is formed from cast iron and said cylinder spaces are provided with smooth liners of another material. 25

17. The combination according to claim 12, in which said pump casing is formed from cast iron and said cylinder spaces are provided with steel liners. 30

18. The combination according to claim 4, in combination with a pump piston in said pump cylinder space, and means for maintaining the amount of fuel returning to said return passage 35 substantially constant per working stroke of said piston.

19. The combination according to claim 4, in combination with a pump piston in said pump cylinder space, and a control groove fixed on said piston, communicating with said cylinder space and opening and closing said return passage at a constant point of time during the stroke of the pump piston to maintain the amount of fuel returning to said return passage substantially constant per working stroke of said piston. 40

20. The combination according to claim 4, in combination with a pump piston in said pump cylinder space, said piston being provided with a control edge oblique to the axis of said piston for controlling the connection between said inlet passage and said cylinder space, and with a control groove extending substantially perpendicularly to the axis of said piston for controlling the connection between said return passage and said cylinder space, and means for rotating said piston, whereby the time relationship of the control of the connection between said inlet passage and said cylinder space may be varied while that of the control of the connection between said return passage and said cylinder space remains substantially constant per working stroke of said piston. 45

21. The combination according to claim 4, in which said last means decreases the amount of fuel flowing to the engine upon an increase of pressure of the amount of return fuel. 50

22. In a fluid pump including at least one pump cylinder space having a piston therein, an inlet passage connected to said cylinder space, a delivery passage leading from said cylinder space, a return passage leading from said cylinder space, and regulating means in said inlet passage responsive to the pressure within said 70

return passage for varying the amount of fluid supplied to said cylinder space.

23. The combination according to claim 22, in which said regulating means includes a slide valve mounted for reciprocal movement in said inlet passage.

24. In a fluid pump including at least one pump cylinder space having a piston therein, an inlet passage connected to the cylinder space, a delivery passage leading from the cylinder space, a return passage leading from said cylinder space to said inlet passage, and regulating means in said inlet passage responsive to the pressure differential between said inlet and return passages for varying the amount of fluid supplied to said cylinder space, said regulating means including means intermediate said return and inlet passages having an interconnecting throttling bore for establishing a pressure differential between said inlet and return passages. 15

25. In a fluid pump including at least one pump cylinder space having a piston therein, an inlet passage connected to the cylinder space, a delivery passage leading from the cylinder space, a return passage leading from said cylinder space to said inlet passage, and regulating means in said inlet passage movable in one direction or the other in accordance with the difference in pressure within said inlet and return passages for varying of the amount of fluid supplied to said cylinder space, said regulating means including means intermediate said return and inlet passages having an interconnecting throttling bore for establishing a pressure differential between said inlet and return passages. 20

26. The combination according to claim 25, in combination with spring means for opposing movement of said regulating means by the pressure within said return passage. 25

27. In a fluid pump including at least one pump cylinder space having a piston therein, an inlet passage for said cylinder space, a canal in said pump, opening into said inlet passage and said cylinder space for conducting fluid to the latter from said inlet passage, a return passage leading from said cylinder space to said inlet passage, and an axially shiftable slide valve movable in one direction or the other in accordance with the difference in pressure within said inlet and return passages for varying the flow of fluid from said inlet passage to said canal, said slide valve including means intermediate said return and inlet passages having an interconnecting throttling bore for establishing a pressure differential between said inlet and return passages. 30

28. In a fluid pump including at least one pump cylinder space having a piston therein, an inlet passage for said cylinder space having a canal leading to said cylinder space, a delivery passage leading from said cylinder space, a return passage leading from said cylinder space to said inlet passage, and an adjustable hollow slide valve open at one end, axially shiftable within said inlet passage and having a radial opening therethrough interconnecting said canal with the hollow portion of said slide valve for controlling the flow of fluid from said inlet passage to said cylinder space, said slide valve being movable in one direction in accordance with the pressure within said return passage, said slide valve including means intermediate said return and inlet passages having an interconnecting throttling bore for establishing a pressure differential between said inlet and return passages. 35

29. The combination according to claim 28, in which said slide valve is formed with a groove of varying depth about the outer end of said opening, whereby a shifting of said slide valve is effective to vary the cross-sectional area of the interconnection between said opening and said canal.

30. In a fluid pump including at least one pump cylinder space having a piston therein, an inlet passage leading to said cylinder space and having a controlling canal, a hollow slide valve axially shiftable within said inlet passage for varying the effective cross-sectional area of said canal, provided with an opening from its outer surface to the interior hollow portion for interconnecting the latter with said canal, and having one end in communication with said inlet passage and the other end with a throttle opening therethrough leading from said inlet passage, a delivery passage leading from said cylinder space, and a return passage for guiding fluid under pressure from said cylinder space against the end of the hollow slide valve provided with the throttle opening.

31. In a fluid pump including at least one pump cylinder space having a piston therein, an inlet passage having an opening into said cylinder space, a hollow cylindrical slide valve having a controlling bore therethrough, mounted for reciprocatory movement within said inlet passage for controlling the flow of fluid through said opening, means for moving said slide valve, and a delivery passage leading from said cylinder space.

32. In a fuel pump having a cylinder space and a piston therein, an inlet passage leading to the pump cylinder space, having a controlling canal, and a second passage leading from the pump cylinder space, the combination of an axially adjustable piston-shaped regulating member in said inlet passage for varying the effective cross-section of said controlling canal, said member being directly subjected on one side to fuel pressure in the passage leading from the pump cylinder space, in such a manner that upon an increase in pressure above a predetermined amount in said second passage, said member is moved to decrease the effective cross-section of said inlet passage and lessen the amount of fuel flowing to the pump cylinder space.

33. The combination according to claim 32, in which said second passage leading from the pump cylinder space is a return passage which carries back a part of the pumped fuel into the inlet passage so that the regulating member acts under pressure of the fuel in said return passage.

34. The combination according to claim 32, in combination with means for adjusting the regulating member at will.

35. The combination according to claim 32, in combination with resilient means for adjusting the regulating member at will, and opposing the action of the return passage pressure upon said member.

SAMUEL MEISWINKEL.
